HEILMAN TYPE COMBER

Frank L. Crockett, East Douglas, Mass., assignee to Whltn Machine Works, Whitinsville, Mass., a Corporation of Massachusetts

Application June 6, 1930. Serial No. 459,576

21 Claims. (Cl. 19—121)

The invention aims to improve the efficiency of Heilman-type combers and consists in a new organization of detaching and piecing mechanism for such machines, according to certain principles herein disclosed and which are capable of application to such machines, in whole or in part and in different ways, and which are exemplified in the accompanying drawings as applied to a cotton comber of the general design of my prior Patent No. 1,671,101 but without limitation to that type of comber.

In the drawings, Fig. 1 shows the principal members of a combing head which directly enter into the present invention, in side elevation and with certain parts broken away for clearness.

Fig. 2 is a front elevation of the piecing and detaching mechanisms of Fig. 1.

Fig. 3 is a diagrammatic section of the piecing action thereof.

Fig. 4 is a vertical transverse section illustrating the relation of the detaching roll to the top comb construction as shown in Fig. 1.

Figs. 5 and 6 represent a modified form of the means for holding the top piecing roll, Fig. 5 is a top plan, broken away and Fig. 6, a section of Fig. 5 on line VI—VI, and

Fig. 7 is a diagram of the piecing action of the rolls as thus arranged.

The numeral 1 marks the frame uprights of the comber upon and between which the respective mechanisms of the several combing heads are mounted; it will be understood that the machine may comprise a series of such uprights mounted upon and along a common base support, according to the number of combing heads in the machine and that the power for driving such heads is ordinarily applied from a drive-head at one end and transmitted to the several combing heads by means of a number of longitudinal shafts extending through them and journaled on the frame uprights, this being the customary organization of combers and not shown by the drawings. All of the combing heads may be alike in construction, so that the description of one will suffice for the whole comber. For clearness of illustration the drawings also omit the weighting stirrups and various other common and necessary apurtenances in cotton combers which however will be readily supplied by the manufacturer.

In the type of machine taken to exemplify the principles of the invention, the nipper frame 2 swings back and forth, being suspended from the upstanding parts of the adjacent frame uprights 1 by means of a pair of forward suspension links

3 and a pair of rear links 4. The upper pivot of the front link 3 is marked 6 and the lower pivot 7 (Fig. 4) and the length of the link is adjustable by use of the nuts as indicated. The swinging movement of the nipper frame is imparted to it by a rear link connection 8 with the crank arm of the nipper rock shaft 8^a which is one of the longitudinal shafts above referred to, receiving its motion from the drive-head at the end of the comber. The nipper frame carries the usual nipper jaws 9, cushion plate and nipper knife, the latter being carried on the nipper levers 9^a, fulcrumed on the nipper frame and operated by engagement with parts in rear which are not illustrated. It also carries the lap-conducting and lap feed mechanism, which is indicated, for convenience, simply by a circle marked 10. In the rearmost position the nippers present the end of the lap to the action of the rotary comb cylinder 5, and in the forward position they deliver it to the detaching rolls and so far as the present invention is concerned it is immaterial how they are designed or operated so long as they appropriately perform these functions.

The top comb also may be variously designed and operated; as here shown the comb blade 11 is mounted on a cross bar 12, see Fig. 4, which is connected by its terminal flanges 13 to the top comb brackets 14, the connection being adjustable as to comb blade angularity by means of the bolt and slot attachment as indicated. The comb brackets 14 are formed with long slots by which they are hung on the studs 15, borne on the rearward head structures 3^a of the front suspension links 3 and in such relation to the latter that as the nipper frame swings forward, the studs move downwards and thereby lower the top comb into the tuft as the latter is being drawn off by the detaching rolls. The lower ends of the top comb brackets 14 are guided, in the present case, by fitting over the gudgeon sleeves of the top detaching roll 17 as shown in Fig. 4, for which purpose they are forked at their lower ends but it will be understood as stated above that the top comb may be otherwise guided and otherwise controlled. When organized as shown the whole top comb structure may be lifted as a unit away from the detaching rolls and slid rearwards on the studs 15 to a position in which the top comb teeth will project forwardly well above the nipper jaw 9 for easy cleaning, this feature being the subject of a co-pending patent, Ser. No. 372,614 filed June 21, 1929.

According to this invention the detaching and piecing functions of the comber are substan-

tially separate, being performed by distinct though related members, that is to say, the drawing off and separation of the tuft from the body of the lap held in the upper frame, and its passage through the top comb teeth, is done by a pair of detaching rolls (16 and 17) and the overlapping of the tufts is done by a pair of piecing rolls (19 and 33) each of which pairs receives a motion appropriate to its particular function. It is sufficient for the detaching rolls, 16 and 17, to rotate continuously in a forward direction, though this is not necessary, and with a constantly uniform speed which is given to the lower roll in the present case by a train of gears being marked 44, 45, 46 and 47 respectively in Fig. 2 direct from the shaft 32 of the comb cylinder. The lower roll 16 may be formed on a continuous shaft, extending through all the combing heads and journalled at 18 on the several frame uprights and the gear-train referred to may be located at either end of that shaft, but preferably at the end of the machine opposite from the drive-head as indicated by Fig. 2. This gear train is omitted from Fig. 1 for clearness, as are also the bearings of the roll shaft 16.

The top detaching roll 17 is driven by its contact with the lower roll 16, being supported thereon by means of the slotted roll holders 17^a fixed to the journal caps 18 by means of the cap bolts of the latter, or otherwise as preferred. The function of these roll holders is to maintain the top detaching roll 17 in proper relation to the lower detaching roll which is preferably a fixed relation, though adjustable, and in such way that the requisite nipping pressure can be imparted to it by means of usual stirrups or other weighting or pressure devices, not shown in the drawings. When properly arranged the detaching rolls are located to seize the head ends of the cylinder-combed tuft which is presented to them by the then opened nippers.

These rolls pass the tuft, which they draw off from the body of the lap, to the two rolling members or rolls 19 and 33 which constitute the piecing mechanism and one or both of which rolls is moved bodily away from and toward the detaching rolls, once for each nip of the machine and in such way as to perform the piecing by overlapping the head end of the tuft emerging on the front side of the detaching rolls on the tail end of the last preceding tuft held by the piecing rolls. See Fig. 3. The piecing is thus done in the space between the detaching rolls and the piecing rolls and not between the detaching rolls and comb-cylinder as heretofore commonly the case. The lower piecing roll, marked 19, is journalled in a movable carriage or support which may be mounted and guided in any suitable way and is represented in the present case by a pair of rocker arms 20, made fast on a shaft 21 which is journalled in the frame uprights and which may be a shaft extending through all the combing heads if desired. It is rocked through an appropriate angle by means of a cam arm 22 fixed at some convenient point thereon and engaged and operated, through its bowl 23, by a disc cam 24, which latter rotates in phase with and may be carried on the comb cylinder shaft 32, a spring being provided to keep the cam bowl 23 in constant contact with its cam as customary with cam motions. The piecing cam 24 is shaped to give one complete excursion to the piecing mechanism for each rotation of the comb cylinder or nip of the comber, and

while other mechanical means might be employed in its place, a simple disc cam constitutes a practical means of producing the desired action.

In addition to its forward and back movement, the lower piecing roll 19 receives also, a rotary motion on its own axis, for which purpose it is provided at its ends or preferably only at one end with a small spur pinion 25, which meshes with and rolls, as a planet gear upon a larger or sun gear 26, the latter being journalled on or concentric with the rock shaft 21. Continuous motion in the direction of the arrow is imparted to the sun gear 26 through a train of gears, marked consecutively 27, 28, 29, 30 and 31, from the comb cylinder shaft 32. The relative arrangement of these gears is indicated in Figs. 1 and 2 and the specific arrangement shown is not essential as the gear 25 can obviously be driven in other ways with equal effect; it is preferred that the sun gear shall be individual to each combing head being therein driven each by its pinion 27 which may be on a common shaft 27^a extending through all the combing heads while the rest of the driving train is located in the drive head at the left end of the machine as indicated in Fig. 2.

The upper piecing roll 33 is held upon the lower piecing roll 19 and driven thereby being under the pressure of suitable stirrups omitted from the drawings for convenience of illustration. As shown in Figs. 1, 2 and 3, the gudgeons or gudgeon sleeves of this top roll are confined in forked slots in an articulated guiding linkage, comprising the connected links 34 and 35, jointed at 36 to brackets 37 fixed to the sides of the frame uprights 1. The lower forked ends of the links 34 straddle the gudgeons of the top roll 33 and extend downwardly far enough to embrace the shaft or axle, or gudgeon sleeves, of the lower piecing roll 19, so that as the latter oscillates back and forth under the action of the piecing cam 24, the top roll 33 is held by the fork slots above, but rolling back and forth upon, and relatively to, the lower roll. The links 34 may rest on the top roll and are readily lifted therefrom when the top roll is to be removed. The dotted lines illustrate the forward position of the lower roll and corresponding position of the top roll.

With the sun gear driven in the direction of the arrow, it will be seen that the two piecing rolls will be rotated in a forward direction on their own axes as they are bodily carried forward or away from the detaching rolls by the movement of the carriage 20, and that they may rotate more slowly or cease their rotation, or may rotate reversely, when making their return stroke, according as whether the rise of piecing cam 24 causes such return stroke to occur more slowly than, equal to, or faster than, the circumferential speed of the sun gear, and within this invention this relation is subject to preference of design according to the type of comber and the nature of the fibres being combed as well as the character of piecing desired, being in this respect capable of modification. The tuft detached by the detaching roll is directed into the bite of the piecing rolls when the latter are in their rear-most position, closest to the detaching rolls, as indicated in the full-line diagram of Fig. 3 and preferably when the piecing rolls have just reached that position, at which they may be assumed to have an appropriate dwell, that is, at the end of the backward stroke, and they are

then driven by the sun gear at a surface speed about the same as that of the detaching rolls or so as properly to take the tuft from them. The control of the movement at this point is indicated by the contour of the cam 24 and enables the piecing rolls to gain a secure nip on the advancing tuft. Immediately that it has been seized, the piecing roll carriage begins to make its forward stroke and at such velocity as will cause the rolls to rotate forwardly with an increased speed as soon as the tuft is clear of the detaching rolls, either uniformly or if desired with an accelerating motion, but in any event, making a quick and clean removal of the tuft from the detaching rolls and passing the greater part of its length through the bite of the piecing rolls. The return stroke of the piecing mechanism is, in the present instance, and preferably, conducted at such a rate as to produce reverse rotation of the rolls, the effect of which is to back the tuft through them to an extent somewhat less than the forward rotation, and by the time the rolls reach their rearmost position, a sufficient length of the tail end of the tuft will be extended rearwards for the next overlap. Such tail end extends downward in the space between the back side of the piecing rolls and the front side of the lower detaching roll 16, in readiness to receive on top of it the head end of the next arriving tuft. In this space or crevice between the two lower rolls, it may be observed that the tuft fibres are free from any snatching effect by the comb cylinder, such as is likely to occur in other types of cotton combers with consequent increase of waste, and since there is no danger of any snatching, it is therefore possible to back the tuft to the fullest extent desired, thereby permitting a longer overlap than could otherwise be safely attempted.

The rolling movement of the top piecing roll, with reference to the axis of the lower piecing roll will be seen to have the effect of bending the tail end of the tuft around upon the back side of the lower piecing roll so that it will be projecting downwardly during the rearward stroke without danger of striking the detaching roll 16 in such a way as to rumple it. Because of the proximity of the two lower rolls it is assumed that the detaching roll 16 may actually have some smoothing effect upon the tail end of the tuft. The action described will be apparent from the diagram in which it will be seen that the top roll is well over on the back side of the bottom roll when both rolls are in their forward position, thus bending the tuft around the roll as stated.

The motion is capable of high speed operation and corresponding efficiency and high speed is also favored by the fact that only the piecing rolls themselves, which are members of relatively small mass, are called upon to reverse their rotation and do so with an easy motion, whereas in prior combers the reversal is commonly performed by relatively massive gearing, in the drive head, which cannot be reversed rapidly without hard shock and noise. The contour of the piecing cam can be made of easy curvature adapted to run smoothly and quietly.

A further feature of the invention comprises means of protecting the tuft from disturbing air currents during the backward swing of the piecing mechanism and is shown in Figs. 5 to 7 as a modified or alternate form of the structure above described. It consists in the use of an extra large sized top piecing roll 38, so mounted and held that it constantly spans and covers as a roof the

space above the tuft for all positions of the parts, thus making the space where the piecing is done a virtually dead space so far as air movement is concerned. As the means for thus closing over the piecing space the use of a top piecing roll of adequate size is preferred, because of its simplicity and its rolling action, and the fact that a roll of such size can be self-weighting if desired. It is held at a fixed distance from the top detaching roll 17 by means of links at each of its ends, such as shown in the figures referred to and so that its path of movement is in a short vertical arc about the axis of that roll as a center as the lower piecing roll moves back and forth beneath it, but with reference to the lower piecing roll it has substantially the same rolling motion, as above described and bends down the tail end of the tuft on the lower roll when in its forward position. See Fig. 6. The links, as shown, consist of two small blocks 39 and 40 slipped on the respective gudgeon sleeves 41 and 42 of the two top rolls and united by a screw 43 for adjustment. This screw is set so that the two top rolls have a clearance between them of the order of about .01 inches, thus for practical purposes completely roofing over the space in which the tufts are drawn off, backed and pieced together. From the foregoing description it will be apparent that within the principles disclosed a wide variety of different forms of structure is easily possible of development, without employing the specific means illustrated, and particularly that the relative motions and timing of the piecing and also the detaching rolls can be easily adapted to produce many different effects.

Having now described the invention I claim:

1. In a comber, the combination with means for detaching a tuft from the lap, of piecing mechanism receiving the tuft therefrom and operating means for said mechanism moving it back and forth bodily toward and from said detaching means.
2. In a comber, the combination of rolls for detaching a tuft, the lower of said rolls revolving on a fixed axis, a piecing roll to receive the tuft, and means for forwardly rotating, and forwardly moving the axis of, said piecing roll with reference to said detaching rolls when receiving or piecing the tuft.
3. In a comber, the combination of continuously forwardly-rotating detaching rolls, piecing rolls, and a carriage for the latter moving the axis of one of the piecing rolls toward and from the detaching rolls.
4. In a comber, the combination of fixed detaching rolls, a pair of piecing rolls and operating means therefor which moves the axes of both piecing rolls toward and from said detaching rolls.
5. In a comber, the combination of a pair of continuously forwardly-rotating detaching rolls, swinging nippers for delivering the end of a lap thereto, a piecing roll receiving the detached tuft therefrom and means for coincidentally imparting to said piecing roll a forward rotation and a forward movement of its rotary axis.
6. In a comber, the combination of fixed detaching means, swinging nippers, a piecing roll and means for alternately forwardly and reversely rotating said roll and coincidentally oscillating its rotary axis toward and from said detaching means.
7. In a comber, the combination of detaching rolls rotating on fixed axes, a lower piecing roll, an upper piecing roll, means for holding the

axis of the latter roll, and means for bodily shifting the lower piecing roll under the upper roll, the overlap occurring on the latter roll.

8. In a comber, the combination of detaching mechanism, a bodily oscillated lower piecing roll receiving the tuft from said mechanism and an upper piecing roll supported on the lower roll and having a diameter adapted to close the space between the lower roll and the detaching mechanism.

9. In a comber, the combination of a lower detaching roll rotating on a fixed axis, a piecing roll rotating on an oscillating axis and receiving the tuft from said fixed-axis roll, and means for bridging over and substantially preventing air current through the space between said detaching and piecing rolls.

10. In a comber, the combination of a lower detaching roll rotating on a fixed axis, a pair of piecing rolls having intermittent forward rotation receiving the detached tuft from the detaching roll and adapted to perform the piecing in the space between said detaching and piecing rolls and air-current-preventing means overlying said space.

11. In a comber, the combination of a pair of tuft-detaching rolls, means for driving the same at a forward speed, a pair of piecing rolls in front of said detaching rolls, means for driving them forwardly, and means for rolling the top piecing roll over on the rear side of the bottom piecing roll following the reception of each detached tuft, thereby bending the tail of the tuft over upon the rear face of said bottom roll.

12. In a comber, the combination of a lower detaching roll operating on a fixed axis, a pair of piecing rolls, receiving the detached tuft from the detaching roll, means for forwardly rotating, and forwardly moving the axis of, the lower piecing roll, and means supporting the upper piecing roll in fixed relation to the detaching roll.

13. In a comber, the combination of a pair of fixed detaching rolls and a bodily oscillating piecing roll, and means for continuously rotating the former and intermittently forwardly rotating the latter.

14. In a comber, the combination of detaching mechanism, means for conducting the lap end thereto, a sun gear, and a planetary piecing roll receiving tufts detached by said mechanism, and oscillating in an arc on its sun-gear towards and from said detaching mechanism.

15. In a multi-head comber, the combination of detaching mechanism and a pair of piec-

ing rolls in each head and gear means in each head for locally driving said rolls and a longitudinal shaft common to all of the heads for driving said gear means.

16. The combination in each of the heads of a multi-head comber, of a comb cylinder shaft mechanism to detach a tuft from the lap and means to piece the tufts comprising a roll with a pinion fixed on one end thereof, a gear wheel engaged to said pinion in each combing head, and a shaft common to all of said heads and parallel to said comb cylinder shaft for driving said gear wheel and thereby locally driving said piecing rolls.

17. In a comber, the combination of a pair of piecing rolls one of them having a driving pinion associated therewith, a driving gear for said pinion, means for oscillating the axis of said pinion concentrically to said driving gear and means for operating said driving gear in the direction to move its top side forwardly, said oscillating and driving means being correlated to produce alternating motion of said roll.

18. In a comber, the combination of a fixed detaching roll, upper and lower piecing rolls, a pinion on the end of the lower roll, means for driving said pinion comprising a sun-gear, a carriage for said lower roll adapted to roll the pinion on said sun-gear and means for oscillating the carriage relative to said detaching roll.

19. In a comber, the combination of fixed detaching rolls, piecing rolls, including a lower roll, a rock shaft having a pair of arms supporting said roll, a gear concentric with said shaft connected for driving said roll, and means for independently rocking said shaft and driving said gear at relative speeds suited to produce intermittent forward rotation of said piecing roll.

20. In a comber, the combination of two detaching rolls operating on fixed axes, a lower piecing roll operating on a movable axis, a top piecing roll resting on the lower roll, a pinion connected to said lower roll, a rocking carriage for said roll, a sun-gear concentric with the carriage and meshing with said pinion and means for driving said sun-gear and rocking said carriage.

21. In a comber, the combination of detaching rolls operating on fixed axes, a lower piecing roll operating on a movable axis, a top piecing roll and an articulate link system supporting the same on the lower roll comprising a link embracing the gudgeons of the lower piecing roll.
